UNITED STATES PATENT OFFICE.

WILLIAM STEVER, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

DEVICE FOR TIGHTENING SCREW BOLTS.

Application filed January 20, 1927. Serial No. 162,291.

This invention relates to a device for tightening screw bolts, and more particularly it relates to a device for holding the nut against rotation while the screw bolt is threaded 5 therethrough.

It often occurs that the nut used in conjunction with a screw bolt is inaccessibly located and therefore can not be held against rotation by the ordinary wrench. This is, 10 especially, the case in the construction of automobile bodies of pressed metal stampings where some of the sheet metal panels are fastened together by screw bolts, although of course, there are any number of other instances wherein the device could be used.

The main object of the invention is to provide a simple and inexpensive device for readily holding against rotation the nuts used with screw bolts which otherwise would 20 be practically inaccessible.

Other objects and advantages will become apparent from time to time.

An embodiment of the invention is shown in the accompanying drawing, wherein 25 Fig. 1 is a vertical section through the device;

Fig. 2 is a view similar to Fig. 1, showing a screw bolt securing two members together and the nut and washer therefor being in the 30 device;

Fig. 3 is a top plan view of the device,

Fig. 4 is a section taken on line 4-4 of Fig. 2, and

Fig. 5 is a sectional view, showing the device partly removed from the nut.

The device comprises a long piece of stock 40 forming a handle 1, the upper end of which is laterally bent at right angles to the remainder of the handle to form a wrench portion 2.

The wrench portion is provided adjacent its free end with a square, or other shaped socket as desired, socket 3 for the reception of the bolt nut 4. The bottom of the socket 45 is apertured at 5 to allow the screw bolt to pass therethrough.

The upper surface of the wrench surrounding the socket is countersunk to provide an annular recess 6 for the reception of a washer 50 7. The circumference of this annular recess is such that a portion thereof will lie beyond the free edge of the wrench.

A spring clip of substantially Z shape has an end 8 secured to the handle 1 and its

intermediate section 9 extending diagonally 55 upward beneath the wrench so as to end adjacent the lower free edge thereof. The other end 10 of the spring clip extends upwardly and inwardly from this point and is provided at its upper end with an enlargement 11. 60 The inner side of the enlargement is provided with an arcuate cutaway portion 12, which serves to complete the annular recess 6.

In practice the screw bolt 13 is passed through the two members 14 and 15, which 65 it is desired to secure together. The nut 4 is then placed in the socket 3 of the wrench and the washer 7 in the annular recess 6, the washer while being inserted in place pushing back the arm 10 of the spring clip. It is perfectly apparent that the enlargement 11 and arcuate cutaway portion 12 will serve to hold the washer in place because of the resilient action of the clip, and at the same time, of 70 course, the nut 4 will be held.

The wrench is manipulated by its handle until the inner end of the screw bolt has been located and passed through the openings in the washer, nut, and socket. After this is done, the screw bolt is turned from the outside until the nut is firmly seated. The end of the screw bolt bearing on the spring clip will also tend to force the nut to ride upwardly on the bolt.

It will thus be evident that a simple, inexpensive and practical device for reaching and holding inaccessible nuts against rotation is provided by the invention, and the various adaptations which it may take is only limited by the scope of the claims.

I claim:

1. A device for tightening screw bolts comprising a handle having a laterally extending portion, said portion having a socket with an aperture in its base for the reception of a nut and the passage of a screw bolt, and means arranged above said socket for receiving and holding a washer, a part of said means being secured to the handle below the laterally extending portion, and yieldingly engaging the washer.

2. A device for tightening screw bolts comprising a handle having a laterally extending portion, said portion having two superimposed recesses communicating with each other, one of which is adapted to receive a nut and the other of which is adapted to receive a washer, a spring member secured to

the handle and cooperating with the washer receiving recess to complete the circumference thereof and to hold the washer in place.

3. A device for tightening screw bolts comprising a handle having an extended portion, said portion having a socket with an aperture in its base for the reception of a nut and the

passage of a screw bolt and a seat arranged above said socket for receiving a washer and means yieldingly holding said washer on its seat. 10

In testimony whereof he hereunto affixes his signature.

WILLIAM STEVER.
